UNITED STATES PATENT OFFICE.

JAMES I. HOLCOMB AND JACOB F. HOKE, JR., OF INDIANAPOLIS, INDIANA.

DESIGN FOR A VENDING-CABINET.

59,006.

Specification for Design.

Patented Sept. 13, 1921.

Application filed November 1, 1920. Serial No. 421,192. Term of patent 14 years.

To all whom it may concern:

Be it known that we, JAMES I. HOLCOMB and JACOB F. HOKE, Junior, citizens of the United States, residing at Indianapolis, in the county of Marion and State of Indiana, have invented a new, original, and ornamental Design for a Vending-Cabinet, of which the following is a specification, reference being had to the accompanying drawing, forming part thereof.

The figure is a perspective view of the vending cabinet, showing our new design.

We claim:

The ornamental design for a vending cabinet, as shown.

JAMES I. HOLCOMB.
JACOB F. HOKE, JR.
